BRONCHOSCOPE WITH ILLUMINATING SYSTEM

Thomas F. Aiken, San Fernando, Calif.

Application November 29, 1954, Serial No. 471,636

8 Claims. (CL 128-6)

This invention relates to surgical devices of the type intended for insertion into a body cavity to illuminate the cavity for visual inspection and to permit the insertion and manipulation therethrough of various surgical instrumentalities. For the purpose of disclosure and to illustrate the principles involved, the invention will be described herein as embodied in a bronchoscope. It is to be understood, however, that the invention is not strictly limited to this particular surgical device.

One problem to which the invention is directed is to provide a device of this character that is of simple and inexpensive construction. Another problem within the purview of the invention is to provide such a device that may be cleaned and sterilized between periods of use in a convenient manner and without requiring troublesome and time consuming assembly and disassembly operations. A third problem in mind is to incorporate a simple illumination system in such a device that will provide adequate illumination at a desirable illumination angle and will offer minimum interference with the manipulation of the device.

In the preferred practice of the invention these problems are met successfully by making the device in the form of an appropriately shaped single block of suitable plastic material that has the property of transmitting light therethrough by internal reflection. The single block of plastic, which preferably has a generally cylindrical external configuration is formed with two longitudinal passages. One of the longitudinal passages is of relatively large cross sectional area to provide for communication with the body cavity and to make visual inspection of the cavity possible. The other longitudinal passage is of smaller cross sectional area and may be curved laterally at its leading end, if desired, to open onto the periphery of the plastic block. This second passage may be used for inserting a surgical device into the body cavity.

A suitable light source in the form of a small electric lamp is positioned to direct light into the material of the plastic block longitudinally thereof thereby to cause the light to be emitted from the leading end of the block. One feature of the preferred practice of the invention in this regard is the forming of the plastic block with an angular end face at the leading end of the larger longitudinal passage so that the emitted light is directed at an angle across the extended axis of the passage. By virtue of this arrangement the surface of the body cavity at the inner or leading end of the device will be illuminated by cross light to bring the surface texture of the cavity into relief. The direction of the cross light may be varied at will simply by rotating the plastic block about its longitudinal axis.

The preferred practice of the invention is further characterized by the concept of employing a plastic block of cylindrical configuration with a cylindrical enlargement at its outer end to serve as a convenient handle for holding the device and for rotating the device about its

2

longitudinal axis. In this regard a feature of the invention is the provision of a peripheral recess in the form of a blind radial bore in the cylindrical enlargement of the plastic block, the purpose of this bore being to house a light source in the form of a lamp bulb. Thus the lamp bulb is positioned within the configuration of the plastic block out of the way instead of being at an interfering position outside the outer end of the plastic block.

A further feature is the concept of frictionally mounting the lamp bulb in the radial bore in a conveniently removable manner. Such an arrangement permits the lamp to be withdrawn when the device is to be cleaned and sterilized, the withdrawal of the light source leaving a single monolithic plastic block with all of its surfaces accessible for cleaning and sterilizing operations.

The various features and advantages of the invention will be apparent from the following detailed description considered with the accompanying drawing.

In the drawing, which is to be regarded as merely illustrative:

Figure 1 is a side elevation of the presently preferred embodiment of the invention as a bronchoscope;

Figure 2 is a longitudinal section of the device on an enlarged scale;

Figure 3 is a side elevation of the device taken at 90° from the section shown in Figure 2;

Figure 4 is a transverse section taken as indicated by the line 4-4 of Figure 3; and

Figure 5 is an end view of the device.

The drawing shows a single body or block, generally designated B, of plastic material of a type capable of transmitting light by internal reflection. The body may be made of any well known plastic of this character, such as polytrifluorochloroethylene.

In the present embodiment of the invention the body B is in the form of an elongated barrel or rod 10 of cylindrical external configuration having a radial or cylindrical enlargement 12 at its outer end. Preferably the elongated barrel 10 has an inclined leading face 14 at its inner end, this face being in a plane at an acute angle to the longitudinal axis of the barrel. At the other or outer end of the device the cylindrical enlargement 12 has an outer face 15 which may be substantially perpendicular to the axis of the longitudinal barrel 10.

The plastic block or body B has a first longitudinal passage 16 of relatively large cross sectional area that extends from one of the end faces to the other. In the present embodiment of the invention, this first longitudinal passage 16 is a straight unimpeded passage to provide free communication with the interior of the patient's lungs for the purpose of free breathing and also to permit visual inspection of the lung tissue and insertion of a right angle viewing instrument. Preferably the longitudinal passage 16, to gain the largest cross section possible, is of a semi-circular cross sectional configuration so that the passage has a flat side 18.

A second smaller longitudinal passage 20 of circular cross sectional configuration is positioned centrally of the body near the flat side 18 of the first longitudinal passage 16. This second passage 20 extends inward from the outer face 15 of the body and at its leading end is curved laterally as shown at 22 to open on the periphery of the elongated barrel 10 near the inclined leading face 14. The purpose of this second longitudinal passage 20 is to permit the insertion of an instrumentality such as a catheter for withdrawing liquids.

A light source may be provided in any suitable manner to direct light into the material of the body B longitudinally thereof to cause the light to be emitted from the inclined leading face 14. In the construction shown, a blind radial bore 24 is provided in the cylindrical en-

largement 12 to house a suitable light bulb 25. It will be noted that the radial bore positions the light bulb 25 within the zone of the circumference of the elongated barrel 10, but, of course, outside the cross sectional areas of the two longitudinal passages 16 and 20. In this position the light bulb 25 directs light into the material of the plastic body B in a direction longitudinally of the elongated barrel 10 and causes the light to be emitted from the inclined leading face 14. Preferably the lamp bulb is provided with a suitable reflector (not shown) to reflect light from the lamp bulb in the desired longitudinal direction. In the preferred practice of the invention, the lamp bulb is carried by a plug-in assembly or fitting 26 on the end of an electric cord 28, this fitting being constructed and dimensioned to fit frictionally in the radial bore 25 in an easily removable manner.

The manner in which the invention serves its purpose may be readily understood from the foregoing description. With the device assembled for use, as shown, it may be readily inserted into a patient's lungs and when so inserted the first longitudinal passage 16 will permit the patient to breathe with ease. The interior of the lungs may be observed through the same longitudinal passage 16 by light that is emitted from the inclined leading face 14. Thus the device illuminates the texture of the tissues in relief by cross lighting and the direction of the cross lighting may be varied at will simply by rotating the device about its longitudinal axis.

Any appropriate instrumentality may be inserted through the second longitudinal passage 20. For example, as heretofore stated, a catheter may be inserted through this second passage to withdraw fluids from the trachea and bronchi. It will be noted that the light source in the radial bore 24 is out of the way and permits the cylindrical enlargement 12 to serve as a convenient handle for freely manipulating and rotating the device as desired, as well as for manipulation of the catheter.

It is an extremely simple matter to withdraw the plug-in lamp fitting 26 in preparation for cleaning and sterilizing operations, and it is an equally simple matter to replace the plug-in lamp fitting to ready the device for use. With the lamp fitting removed, only the single plastic body B remains and it is apparent that the plastic body may be totally immersed in any desirable sterilizing fluid. It is contemplated that the plastic material of the body B will be of a character capable of withstanding temperatures substantially higher than 212° F. so that the body may be sterilized by boiling water or by steam and may be placed in an autoclave for this purpose.

Although the now preferred embodiment of the present invention has been shown and described herein, it is to be understood that the invention is not to be limited thereto, for its is susceptible to changes in form and detail within the scope of the appended claims.

I claim:

1. A surgical device of the character described comprising: a block of generally cylindrical external configuration for insertion into a body cavity, said block having a first longitudinal passage of generally semi-circular cross-sectional configuration for communication with and visual inspection of a body cavity and having a second longitudinal passage curved at its leading end to open on to the periphery of the block for the insertion of a surgical instrument into the body cavity; and a light source mounted on said block to direct light into the material of said block longitudinally thereof for illumination of the body cavity, said light source being positioned within the outer circumference of said block but outside of the cross-sectional areas of said passages, said block being made of material capable of transmitting light therethrough by internal reflection for emission of the light from the end of the block.

2. A surgical device of the character described comprising: a block of plastic material of generally cylindri-

cal external configuration for insertion into a body cavity and with an enlargement at one end to serve as a handle and having a recess therein, said block having a first longitudinal passage for communication with and visual inspection of the body cavity and having a second longitudinal passage for the insertion of a surgical instrument into the body cavity, said second longitudinal passage being curved to open at its leading end on the periphery of the block near the leading end of the block; and a lamp in said recess in the handle portion of said block to direct light into said plastic material longitudinally of the block, said plastic material being capable of light transmission therethrough by internal reflection to cause light to be emitted from the leading end of the block.

3. A surgical device as set forth in claim 2 in which said recess is on the side of said second longitudinal passage opposite from curvature at the leading end of the passage.

4. A surgical device as set forth in claim 3 in which said first longitudinal passage is of generally semi-circular cross sectional configuration with a flat longitudinal side; and in which said second longitudinal passage is positioned centrally adjacent said flat side.

5. A surgical device of the character described, comprising: a body member of a transparent material capable of transmitting light therethrough by internal reflection, said body member including a generally cylindrical rod having an enlargement at one end thereof, said rod being insertable into a body cavity, said body member

30 having a first longitudinal passage therethrough for communication with and visual inspection of the body cavity and having a second longitudinal passage therethrough for the insertion of a surgical instrument into the body cavity, said first longitudinal passage having a substantially semi-

35 circular cross-sectional area in a direction transverse to the axis of the cylindrical rod and said second longitudinal passage having a substantially circular cross-sectional area in the transverse direction, said second longitudinal passage being disposed on the non-circular side of

40 the first passage, said second longitudinal passage opening onto the end of the rod opposite said enlargement adjacent the opening thereof of the first passage; and a light source mounted on said enlargement to direct light into the material of the body member and longitudinally of the rod thereof for illumination of the body cavity, said light source being positioned within the outer circumference of said enlargement but outside of the cross-sectional areas of said passages.

6. A surgical device as set forth in claim 5 in which 50 said rod has an inclined end face at the end opposite said enlargement onto which said first passage opens, thereby to emit the light at an angle across the axis of the first passage whereby the cavity tissue in the region of the first passage is illuminated by cross light.

7. Surgical apparatus of the character described, including, a body member of a transparent material capable of transmitting light therethrough by internal reflection, said body member including a generally cylindrical rod having an enlargement at one end of the rod, said rod 60 being insertable into a body cavity, said body member having a first longitudinal passage therethrough for communication with and visual inspection of the body cavity and having a second longitudinal passage therethrough for the insertion of a surgical instrument into the body cavity, said first longitudinal passage having a substantially semi-

65 circular cross-sectional area in a direction transverse to the axis of the cylindrical rod and said second longitudinal passage having a substantially circular cross-sectional area in the transverse direction, said second longitudinal passage being disposed on the non-circular side of the first passageway, said first and second longitudinal passages extending through the rod and communicating with the atmosphere at the end opposite the enlargement, said enlargement being of a generally cylindrical configuration axially aligned with the axis of the rod and

70 75

having a socket for receiving a light source for mounting on said enlargement to direct light into the material of the body member for travel of the light through the body member to illuminate the cavity.

8. A surgical apparatus as set forth in claim 7 in which the rod has an inclined face at the end opposite the enlargement to obtain the emission of light in a direction transverse to the axis of the cylindrical rod and in a direction dependent upon the rotational disposition of the rod.
